SWITCH FOR USE IN TELEPHONE SYSTEMS

Fritz Döring, Berlin-Frohnau, and Konrad Müller, Berlin - Siemensstadt, Germany, assignors to Siemens & Halske Aktiengesellschaft, Berlin-Siemensstadt, Germany, a German company

Application May 4, 1932, Serial No. 609,142
In Germany May 4, 1931

11 Claims. (Cl. 179—27.53)

The invention relates to switches for communication systems, particularly telephone systems, and especially to switches the wipers of which execute a rectilinear movement. Switches of this type in the telephone art are named rod switches.

Difficulties are experienced with regard to switches of this type when the wipers are to be brought to rest on a definite contact, for example, the called subscriber's contact or the contact of an idle line, the difficulty being to carry out this operation as reliably as other switches, such as for example rotary switches. This is mainly due to considerable power being required for a rectilinear setting movement in order 15 to attain the required setting speed which may only be achieved by means of larger and more powerful driving devices. Comparatively complicated and uneconomical auxiliary devices are necessary to handle the movable members in rod 20 switches of known types.

The object of the present invention is to produce a rod switch combining a most reliable operation with greatest possible economy in the system and this is achieved by causing the rotatable member of a device driven by an electric motor of the type disclosed in our co-pending application, Serial No. 577,672 filed Nov. 27, 1931, to actuate power transmission devices which impart a rectilinear setting movement to the switch 30 wipers.

Due to the use of the driving device disclosed in the above co-pending application the switch may be brought to rest in a reliable manner even at very great setting speeds owing to the fact that the total weight of the movable mass is comparatively small. The invention, therefore, is particularly suitable for switches having a single set of wipers brushing several or all the contact groups instead of separate sets of wipers for each contact 35 group.

An additional feature of the invention is that a transmission drive is arranged between the power transmitting devices which actuate the switch wipers and the switching means (switch contacts) controlling the movement of the switch. The said transmission drive is so constructed that it may form contact groups embracing a variable number of contacts of the contact bank. A further means for reducing the size of the movable mass according to the invention, is that the leads to the wipers are suitably connected up within the movable range of said wipers in or near the centre, with the result that the wiper carrier, when actuated, will not have to carry the total 50 weight of the whole length of lead extending

from the wiper to the complete range of contacts to be brushed, but only a part thereof.

The smallest possible movable mass may be utilized if the movable member of the device (i. e. the armature) driven by an electric motor is 60 coupled direct to the power transmission devices (i. e. the spindle) which transmit the movement to the wiper carrier.

An embodiment of the switch arrangement according to the invention is fully described in conjunction with the accompanying drawings.

Fig. 1 represents a side view of the switch in which the double sided contact of the switch is shown in section.

Fig. 2 shows a view of the switch.

Fig. 3 a view of the said switch seen from above.

Fig. 4 the cam actuated switch contacts seen from above and arranged beneath the motor.

Figs. 5 to 10 inclusive illustrate various views of an embodiment which demonstrates the method of exchanging spindle or guide rods.

Fig. 11 shows a section of a rectangular guide rod and the manner in which it has been arranged.

Figs. 12, 13 and 14 show an embodiment of an arrangement at the use of which the size of the contact groups may be determined according to requirements.

Fig. 15 shows the controlling circuits for the switch and its application as a group selector.

The reference numeral 1 represents a device, driven by an electric motor the construction of which is fully described in co-pending application Serial Number 577,672. For this reason the drive mentioned has been only diagrammatically 90 shown in Figs. 1 and 2. The armature of the electric motor is coupled direct to the spindle 2. The threaded wiper carrier 3 which is provided with the contact wipers 5, 6 and 7, comprising a pair of springs each, and an interposed fibre disc 4, 95 slides on said spindle. In order to prevent the wiper carrier 3 from taking part in the rotary movement when the spindle is rotated a guide rod 8 is provided. The arrangement of the three contact wipers, combined in a set, in the manner 100 illustrated in Fig. 3, shows the central switch wiper 6 passing between the spindle 2 and the guide rod 8 while the other two wipers 5 and 7 are arranged on either side of the said rod. Current is applied to the wipers over the lead 12. 105 Parallel to the spindle 2 or to the guide rod 8 a third rod 20 is arranged, to the approximate middle of which the lead 12 is connected in some suitable manner, for example, by means of a clamp so that the whole weight of the lead 12 110

need not be carried when the wipers are actuated. Angular brackets 9, suitably fixed to the flat contact bank 10, act as bearings for the spindle or for the rod 8. Close to the motor, at the end on the one side of the track followed by the returning wiper carrier 3, a set of contact springs 21, 22, 23 are disposed on a U-shaped carrier 29. The set of springs 23, under the influence of a spring 27 is pressed by the wiper carrier 3, against two fixed stops 28 of the wiper carrier, whereas the sets of springs 21 and 22 are actuated by catches 25 and 26 fixed to said wiper carrier. These catches pivot on the screw 24 and are adapted to operate independently of each other in such a manner that the set of springs 21 and 22 are actuated only when the wiper carrier moves forward but not during its backward movement. This arrangement is incorporated in the circuit provided for the switch.

The lower end of the spindle 2 extends beyond the device driven by an electric motor and in this end carries a small toothed wheel 13 engaging a larger wheel 14 of the same type. The toothed wheel 14 as well as the two cam discs 15 which actuate additional sets of contact springs 16 are fixed on the shaft 18 pivoted in the bearing 19. The leads to the sets of contact springs 16 are represented by the reference numeral 17. The contact springs 16 are actuated at regular intervals when the spindle 2 rotates due to the transmission ratio of the toothed wheels 13 and 14 and to the action of the cam faces 15. Thus, it will be found, that the wiper carrier, when actuating the sets of contact springs 16, has covered a definite distance or in other words, has brushed a definite group of contacts 11.

The contact bank 10, shown diagrammatically in section, together with the fixed contacts 11, forms a suitable multiple bank allocated in common to a plurality of switches, that is to say, it forms a contact bank of such a type that the multiple connections are found within the bank proper. As will be seen in Fig. 1 the bank 10 forms a double sided multiple bank with the object of being able to adapt the back of it also for the provision of switches. The dotted lines in Fig. 2 show diagrammatically a second switch arranged on the same bank 1. Fig. 4 illustrates the form of the cam faces 15 provided and adapted to actuate the set of springs 16.

Figs. 5 to 10 inclusive give illustrations of an embodiment showing the manner in which the spindle as well as the guide rod may readily be exchanged. The top and bottom bearings for the spindle and guide rod are shown in section in Figs. 5 and 8. An angular bracket 30 is fixed to the contact bank 1 at the upper end of the spindle and is provided with two holes 31 and 32. A bearing bush 34, partly riveted to the member 33, is pivoted in the bore 31, whereas in the bore 32 is fitted the washer 35, firmly secured between the nut 36 and the member 33 by tightening said nut, and rigidly connected to the guide rod 8. The facility is thus provided of being able to remove forthwith the member 33 together with the spindle 2 and the guide rod 8 from the angular socket 30 by drawing it downwardly. As shown in Fig. 7 the member 33 is L-shaped so that the rod 20 which serves to fix the lead together with the guide rod 8 forms a rigid frame. Another angular bracket 37 is fixed to the bank 1 in the lower end of the guide rod 8 and the form of said angular bracket will be seen in Fig. 10, which shows a plan thereof. Similarly at the upper end of the guide rod, a washer 39 is rigidly

connected to the member 38 by means of the screw 40 and disposed in the recess 41 in the member 37. A bush 43 is firmly riveted to the member 38 for the spindle 2 and the upper portion of said bush is disposed in the recess 42 of the member 37. After disposing the bush 43 or the washer 35 in the upper angular bracket 30 and then pushing the bush 43 as well as the washer 39 into the forked recess 41 and 42 of the member 37, the screw 44 which is undetachably fixed to the member 37, is tightened whereupon all the members are secured in their appropriate positions.

According to Fig. 11 the guide rod 8 is of square section and is pressed by means of a flat spring 45 against the wall of the opening provided for the guide rod in the wiper carrier 3. The spring 45 prevents the wipers on said wiper carrier 3 from getting out of alignment.

Fig. 12 shows a plan of a contact arrangement which may be used instead of the contact arrangement 15, 16 shown in Figs. 1 and 2 and by the use of which the size of the contact groups brushed by the wipers may be altered according to requirements. The not shown spindle 2 is provided with a small toothed wheel 46 engaging the toothed wheel 47. This toothed wheel 47 in turn actuates the toothed disc 48 which is provided with pins 49 fixed at various points along the periphery. The pins are adapted to actuate the set of contact springs 50 suitably fixed on the supporting base 51. The toothed wheels 47 and 48 rotate in the bearings 52 and 53. The contact group to be brushed by the wipers can be altered either by exchanging the toothed wheel 48 or by arranging the pins 49 individually at various points along the periphery of the disc 48 in which case the pins are detachably arranged.

Fig. 13 shows a front view of the above described arrangement, whereas Fig. 14 represents a side view thereof.

If the armature of the device, driven by an electric motor, is coupled direct to the spindle, the spacing or distance of the contact laminations on the contact bank is so calculated that it shows a definite ratio in relation to the pole spacing of the device, driven by an electric motor. The space between each lamination then equals the multiple pole spacing, that is to say, if, for example, the armature executes a movement from pole to pole, the wiper carrier is moved from one lamination to another due to the correspondingly calculated distance which the spindle moves. A toothed wheel transmission upon the ratio of which depends the distance covered by the wiper carrier may also be disposed between the spindle and the rotating member of the device driven by an electric motor.

In many instances it is an advantage to couple the device driven by an electric motor to the power transmission devices in such a manner that a relative movement between the wiper carrier and the rotating member of the device driven by an electric motor may take place when the switch is brought to rest. This may be effected either by means of a flexible coupling fitted between the rotating member of the device driven by an electric motor and the spindle or else by means of a clutch coupling, that is to say, a coupling which permits the rotating member of the device driven by an electric motor to carry out a few more revolutions when the spindle is stopped by mechanical means such as for example a locking pawl. When a flexible coupling

is used between motor and spindle when this is to be brought to rest, the armature runs past the stator pole which is energized for the purpose of stopping the motor and, under the influence of the spring coupling or the energized stator pole, swings backwards and forwards until finally brought to rest opposite the pole.

Instead of using a spindle as a power transmission device other devices may also be provided such as, for example, a chain to which the wiper carrier is fixed, a steel band or some other power transmission device known per se.

A description will now be given of the operation of the switch when used as a group selector, reference being had for this purpose to Fig. 15.

When the group selector switch shown is seized, relay C energizes over the c-lead. Relay A responds to impulses transmitted over the a-lead and upon its first operation closes the circuit for relay V which energizes and due to its short circuited winding remains energized for the duration of the impulse series. Relay V closes a circuit for the motor which extends over contacts of relay C. The cam contacts Kw H R and Kw Zw in conjunction with contacts of relay A control the motor and cause the switch to move at high speed from group to group of contacts. It should be noted that the cam contacts Kw H R and Kw Zw correspond to the contacts 16 shown in Fig. 4. The group control is effected by the cam contacts in substantially the manner shown in Fig. 11 of our copending application Serial No. 577,672. At the end of the impulsive relay V releases and short circuits the damping windings m_1 and m_2 arranged on the stator magnets M1, M2 of the motor. Consequently the switch now operates at a lower speed and free hunting takes place over the contacts of a group. The circuit to the motor is now maintained over back contacts of relays V and P2, from contacts of relay C and off normal contacts k. When an idle line is found relay P1 energizes over the c-lead and maintains the coils M1 and M2 energized from earth at contacts of relay C. Relay P1 also closes the circuit for relay P2 which energizes. Relay P2 upon operation, opens the circuit to the motor and switches through the a and b leads.

If it should happen that all the lines in the group are busy the switch will be stopped at the end of the grip due to the energization of relay P1 in exactly the same way as if an idle line had been reached.

The release of the switch is initiated upon the de-energization of relay C. Relay C upon de-energizing closes a circuit for relay Ru over off normal contacts k and this relay upon operation causes the reversal of the current in the motor and also connects up an alternative earth to complete the circuit of the motor in place of the earth disconnected at contacts of relay C. Due to the reversal in the direction of the current to the motor the motor rotates in the opposite direction and consequently the switch restores to normal.

When the switch reaches its normal position the off normal contacts k restore and holding earth is applied to the motor over one of these off normal contacts and front contacts of relay Ru in order to bring the switch to rest. The off normal contacts k correspond to the sets of contacts 21, 22, 23 shown in Figs. 2 and 3. One of these off normal contacts k upon restoring opens the circuit of relay Ru which thereupon restores. The switch is now fully restored to normal and is in a condition for re-operation.

What we claim is:—

1. In a switch structure, wherein a set of movable wipers are arranged to successively engage the contact sets of a bank of fixed contact sets, and wherein after having been moved into engagement with one set of such contacts are later moved to their initial position by retrograde movement, the provision of a mechanical arrangement comprising a threaded spindle, equipped with a wiper carrier threaded thereto, of a guide for preventing rotation of the wiper carrier with the spindle, and of means for rotating the spindle in one direction the distance required to selectively associate the wiper set with any desired one of said contact sets and for then restoring the wiper carrier and its wipers by rotating said spindle in the reverse direction. 80

2. In a switch structure such as covered by the preceding claim, characterized in that, off-normal springs are arranged to be moved to their alternate positions consequent to movement of the wiper carrier from its normal position. 95

3. In a switch structure, wherein a set of movable wipers are arranged to successively engage the contact sets of a bank of fixed contact sets, and wherein after having been moved into engagement with one set of such contacts are later moved to their initial position by retrograde movement, a driving means having a wiper carrier supported thereon from the end thereof nearest the bank and having the wipers secured thereto on the opposite end thereof, whereby the over-all depth of space occupied by the wipers and their driving means is maintained at a minimum. 100

4. In a switch mechanism wherein a set of wipers has access to groups of fixed contacts, an electric motor and cooperative gear train for moving the wipers over the groups of fixed contacts, circuit switching springs for controlling said motor as required to drive the switch wipers from one group of contacts to the next each time the motor is energized, and means enabling the adjustment of said circuit switching springs to be modified to accommodate various sized 115 contact groups. 120

5. In a switch structure, a bank of fixed contacts arranged in a vertical plane, brackets fixed to said bank above and below said contacts, an operating assembly cooperative with said bank of 125 contacts, and means for removably securing said assembly to said brackets.

6. In a switch structure, a bank of fixed contacts arranged in a vertical plane, brackets fixed to said bank above and below said contacts, an 130 operating assembly cooperative with said bank of contacts including; a spindle having a wiper assembly threaded thereto, a guiding rod for said wiper assembly, a wiper cord holding rod, and end elements securing said spindle and rods in 135 fixed relation to each other; and means for removably securing said assembly to said brackets.

7. In a switch mechanism, a bank member having the surface of a plane, sets of contacts protruding from said bank and arranged in a 140 straight line, a spindle mounted on said bank in spaced relation therefrom, a wiper carrier threaded on said spindle and equipped with wipers arranged to engage said sets of contacts, a motor for rotating said spindle in one direction, 145 means for preventing rotary movement of said wiper carrier, with a consequent movement of said wipers rectilinearly through the medium of their carrier successively into engagement with said contacts, and means for then reversing the 150

- direction of rotation of said motor to restore said wipers to their initial position.
4. In a switch mechanism, a bank of contacts arranged in a straight line, a set of wipers arranged for movement into consecutive engagement with the contacts of said bank, means for moving said wipers comprising a threaded shaft, means for rotating said shaft in one direction variable distances to bring said wipers into engagement with desired ones of said contacts, and means for then reversing the direction of movement of said rotating means to effect the reverse rotation of said threaded shaft to effect the restoration of said wipers.
- 10 5. In a motor driven switch employing as a source of power a motor equipped with actuating windings and a rotating armature, power transmission devices arranged to impart a rectilinear movement to the wipers of said switch consequent to the rotation of the armature, and circuit switching members rotatable with the motor armature and employed to control its movement.
- 15 10. In a switching mechanism, a set of wipers having a rectilinear path of movement, fixed
- 20 25. 30. 35. 40. 45. 50. 55. 60. 65. 70. 75. contacts successively engaged by said wipers during their course of movement, an electric motor having a rotating member and an associated power transmission device for imparting the specified movement to said wipers, and other members rotated by said motor employed to control the extent of rotation of the first member and in consequence the extent of movement of said wipers.
- 80 85 90 95 100 105 110 115 120 125 130 135 140 145 150
11. In a switch structure, a bank of contacts, a set of wipers co-operative with said bank of contacts, a threaded spindle equipped with a carrier for said set of wipers; a motor for driving said spindle, the threads of said spindle having a pitch so calculated with respect to the spacing of said contacts and with respect to the distance of rotation of said spindle as determined by the spacing of the pole pieces of said motor that for each stage of movement of the armature of said motor the set of wipers are moved from one contact set to the next adjacent one.
- FRITZ DÖRING.
KONRAD MÜLLER.
